UNITED STATES PATENT OFFICE.

JOSEPH H. RUPP, OF LOWER ALLEN TOWNSHIP, CUMBERLAND COUNTY, PENNSYLVANIA.

ELEVATOR.

1,116,129.

Specification of Letters Patent.

Patented Nov. 3, 1914.

Application filed September 24, 1913, Serial No. 791,579. Renewed September 30, 1914. Serial No. 864,365.

To all whom it may concern:

Be it known that I, JOSEPH H. RUPP, a citizen of the United States, residing in Lower Allen township, in the county of Cumberland and State of Pennsylvania, have invented certain new and useful Improvements in Elevators, of which the following is a specification, reference being had to the accompanying drawings.

10 This invention relates to certain improvements in elevators and has relation more particularly to a device of this general character especially designed and adapted for use in delivering sheaves of grain or the like to the mow of a barn or any other desired locality, and the object of the invention is to provide a device of this general character having novel and improved means whereby the sheaves are readily and effectively engaged and discharged with convenience.

15 The invention consists in the details of construction and in the combination and arrangement of the several parts whereby certain important advantages are attained and the device is rendered simpler, less expensive and otherwise more convenient and advantageous for use, all as will be hereinafter more fully set forth.

20 The novel features of the invention will be carefully defined in the appended claims.

In order that my invention may be the better understood, I will now proceed to describe the same with reference to the accompanying drawings, wherein—

25 Figure 1 is a view in side elevation of an elevator constructed in accordance with an embodiment of my invention; Fig. 2 is a view in front elevation of the device as disclosed in Fig. 1, with certain of the parts being omitted; Fig. 3 is a view in rear elevation of the device, as herein set forth, certain of the parts being omitted and certain of the parts being shown in section; Fig. 4 is a detailed fragmentary view in elevation illustrating certain features of my invention; Fig. 5 is a view in elevation of a winding pulley herein employed; Fig. 6 is a view in side elevation of Fig. 5; Fig. 7 is a view in top plan of the table, herein disclosed, for controlling the adjustment of the chute; Fig. 8 is an enlarged fragmentary view in elevation illustrating certain details of the elevator, as herein embodied;

Fig. 9 is a fragmentary view in front elevation of the device herein disclosed illustrating a certain detail of my invention, as herein embodied; and Fig. 10 is a fragmentary sectional view taken through the mounting of the chute, as herein set forth.

30 As disclosed in the accompanying drawings, 1 denotes an elongated body of material adapted to be supported in any convenient manner in a substantially vertical position and suitably secured to and supported at the upper end thereof is the table 2, the adjacent ends of the body 1 and the table 2 being suitably spaced, as at 3, to permit the projection therebetween of the bight of the roller 4 extending transversely of the body 1 and suitably mounted in the frames 5 herein shown as serving to maintain the body 1 and table 2 in operative relation.

35 The stems of the frames 5 are braced in a well known manner by the straps or arms 6, such straps or arms 6 serving as a mounting for the shaft 7 having fixed at a point substantially intermediate its length the sprocket wheel 8 around which is adapted to pass the sprocket chain 9 which extends from such wheel 8 and around a roller 10 rotatably supported by and between the projected portions 11 of the frames 5 at the outer end portion of the table 2. The chain 9 then passes over the table 2 and around the roller 4 and down the forward face of the body 1 and around a second sprocket wheel 12 fixed to the shaft 14 mounted in the bearings 15 carried by the inner face of the body 1, the end portion of the body 1 being recessed, as at 16, in order to properly accommodate the sprocket 12. The chain 9 then extends upwardly at the rear of the body 1 to the sprocket 8. Any means that will operate with facility may be employed for imparting the requisite movement to the chain 9 which movement is upward relatively to the forward face of the body 1 but I prefer to employ the arrangement shown in the accompanying drawings wherein the shaft 14 is projected to one side of the body 1, as at 17, to which projected portion is affixed the pulley 18 around which is adapted to be passed a belt leading from a suitable source of power.

40 45 50 55 60 65 70 75 80 85 90 95 100 105 The sprocket wheels 8 and 12, as is believed to be apparent, determine the position of the chain 9 which is preferably at

the transverse center of the body 1 and table 2 and suitably affixed at predetermined intervals to the chain 9 are the transverse arms 19 extending to either side of the chain 9, 5 and projecting laterally from the extremities of the arms 19 are the hook members 20, the direction of extension of the hook members 20 being such as to have the hooks of the forward stretch of the chain extended 10 toward the base of the body 1 with the hook portions 21 at substantially right angles to the adjacent face or surface of the body.

When the conveyer is in motion the hook members 20 are caused to engage with the 15 sheaves whereby the same are elevated to the table 2 and from such table 2 are discharged within the chute 22. Adjacent its inner end portion the chute 22 has affixed to its under surface the transversely 20 directed strap 23 provided with the centrally disposed bearing block 24 provided in its under surface with an upwardly directed recess or pocket adapted to accommodate an upstanding lug 25 formed on 25 the outer end of the bracket 26 projecting rearwardly of the body 1 and suitably secured to the frames 5, hereinbefore referred to. The downward movement of the block 24 relative to the finger or lug 25 is limited by its contact with the table 27 suitably affixed to the bracket 26 adjacent the 30 base of the lug or finger 25 and such table 27 is circular in form and is provided in its rear marginal portions with the notches 35 37 adapted to be engaged by the dog 38 normally maintained within one of such notches 37 through the medium of the retractable member 39, herein shown as a coil 40 spring anchored at its opposite ends to the block 24 and the dog 38. This dog 38 is provided with the extension 40 to which is secured the end portion of a flexible member 41, herein shown as directed through a 45 suitable opening 42 produced in the bearing block 24 and directed longitudinally of the chute 22 and passing through an eye 43 or equivalent means depending from the chute adjacent its outer end. The opposite end portion of the flexible member is suitably secured to a spool 44 having the spring 50 flanges 45 adapted to frictionally contact with the flexible member 41 and thereby prevent unwinding of such member 41, yet readily separating when it is desired to 55 wind the member 41 upon the spool as the necessities of practice may dictate. By this arrangement, it will be observed that the chute is effectively locked in its various adjustments and that such chute is readily 60 manipulated through the medium of the flexible connection 41, it being obvious that in order to release the dog or latch 38 it is only necessary to create sufficient pull upon the connection and that with the dog 65 or latch 38 in released position the flexible

member 41 can be readily employed for imparting the requisite adjusting movement to the chute.

Projecting forwardly of the body 1 and operatively supported by one of the frames 70 5 is the horizontal arm 28 in which is rotatably mounted a shaft 29 projecting to either side of said arm 28, and to the outer projected portion of the shaft is affixed a sprocket wheel 30 around which is adapted 75 to pass the sprocket chain 31 which also passes around a larger sprocket wheel 32 mounted on a projecting end 33 of the shaft 7. The relative sizes of the sprockets 30 and 80 32 are such as to cause the shaft 29 to rotate to a greater speed than the travel of the chain 9, for reasons to be hereinafter apparent.

To the inner projected portion of the shaft 29 is removably secured the hub 34 85 provided with a plurality of radially directed stems or shanks 35 terminating in the forks 36. It is thought to be obvious that the movements of the forks 36 will be away from the body 1 and that the stems 90 or shanks 35 are of such a length as to penetrate and engage the sheaves being elevated along the forward surface of the body 1 and to lift or disengage the same from the hook members 20 and throw such 95 sheaves in a direction opposite to the direction in which the table 2 is extended, this being permitted by the relative differences in the speed of travel of the forks 36 and the chain 9. These forks 36 are 100 only employed when it is desired to throw the sheaves forwardly of the support 1 and are therefore removed from operative position when it is desired to extend the sheaves along the table 2. Any suitable means may 105 be employed for holding the hub 34 to the shaft 29.

From the foregoing description, it is thought to be obvious that an elevator constructed in accordance with my invention 110 is of an extremely simple and comparatively inexpensive nature and is particularly well adapted for use by reason of the convenience and facility with which the sheaves may be elevated and delivered as desired, 115 and it will also be obvious from the foregoing description that my invention is susceptible of some change and modification without material departure from the principles and spirit thereof, and for this reason I do not wish to be understood as limiting myself to the precise arrangement and formation of the several parts, herein shown, in carrying out my invention in practice.

125 What I claim is:—

An elevator for sheaves comprising a body, a vertically disposed endless conveyer operatively supported by the body, a forwardly projected arm connected to the body 130

adjacent the upper extremity of the conveyer, a shaft rotatably supported by such arm and projecting at opposite sides thereof, such shaft being disposed in advance of the 5 conveyer and in a plane intersecting the plane in which the conveyer travels, a hub removably secured to the inwardly projected extremity of the shaft and in alinement with the conveyer, radially disposed forks 10 projecting from the periphery of the hub

and adapted to penetrate the sheaves lifted by the conveyer and release the same therefrom, and a driving means for the conveyer and the shaft in advance thereof.

In testimony whereof I hereunto affix my 15 signature in the presence of two witnesses.

JOSEPH H. RUPP.
